Patented Feb. 3, 1925.

UNITED STATES PATENT OFFICE.

LEONARD MICHAEL, OF BROOKLYN, NEW YORK, ASSIGNOR TO AMERICAN CAN COMPANY, OF NEW YORK, N. Y., A CORPORATION OF NEW JERSEY.

CONTAINER.

Application filed June 5, 1922. Serial No. 565,877.

To all whom it may concern:

Be it known that I, LEONARD MICHAEL, a citizen of the United States, residing in Brooklyn, in the county of Kings and State of New York, have invented a new and useful Improvement in Containers, of which the following is a specification.

This invention relates in general to tearing strip cans and has more particular reference to cans of large size and where it would be inconvenient or impracticable to wind a strip from the entire circumference of the body in a single roll upon a key.

An important object of the invention is the provision of a side opening tearing strip can so constructed and arranged that cans of large diameter may be conveniently and expeditiously opened.

Another important object of the invention is the provision of a can of this character, which may be manufactured without greatly additional cost.

Another important object of the invention is the provision of a key for use with such cans and others which may receive separate strip parts together constituting the entire encircling strip and retain them after opening.

Other objects and advantages of the invention will be apparent as it is better understood from the following description, which, taken in connection with the accompanying drawings, discloses a preferred embodiment thereof.

35 On the drawings,

Figure 1 is a side elevation of a can embodying my present invention;

Fig. 2 is a similar view taken from the opposite side and after the initial steps in 40 the opening of the can have been made;

Fig. 3 is a plan view of a blank adapted for the manufacture of the body of the can shown in Figs. 1 and 2;

Fig. 4 is a transverse section taken horizontally through the tearing strips in Figs. 45 1 and 2; and

Fig. 5 is a key.

For the purpose of illustrating my present invention I have shown on the drawing 50 a large diameter can, in which it is embodied. This can comprises in the present instance a circular sheet metal body 11 formed of a blank as shown in Fig. 3, preferably of tin-plate, and has its side edges 55 seamed together at 12. A tongue 13 extends

beyond this seam at one point and is arranged between two encircling score lines 14. At a point circumferentially remote from the seam 12 a transverse scoring 15 is provided across the strip area between the score 60 lines 14. A tongue 16 is arranged in the present instance within the container and is soldered at 17 to the strip area of the blank before the body is formed, the tongue extending over behind the transverse scoring 65 15 in the same angular direction as the tongue 13.

Referring to Fig. 5, reference character 18 indicates a key differing from the ordinary key in the provision of two flattened 70 portions in each of which is provided a tongue receiving slot 21. When it is desired to open the can the slot nearer the handle 22 of the key is threaded over the tongue 13 and the key turned to remove a strip from 75 between the points *a*—*b*, the direction of movement being a clockwise one, and up over the top in Fig. 3. When the strip severing reaches the point *b*, i. e. the score line 15, the strip tears away. Thereafter the tongue 16 80 is bent out and threaded into the slot 21 more remote from the handle 22 and the winding severing strip removing action repeated to remove the strip part located 85 between the points *b*—*a*, movement being in the same angular direction.

It is thought that the invention and many of its attendant advantages will be understood from the foregoing description, and it will be apparent that various changes may 90 be made in the form, construction and arrangement of the parts without departing from the spirit and scope of the invention or sacrificing all of its material advantages, the form hereinbefore described being merely a 95 preferred embodiment thereof.

I claim:

1. A tearing strip can, comprising a body having a pair of score lines encircling it, a plurality of tongues arranged between said 100 score lines and adapted to be successively engaged to permit successive removal of parts of the strip area defined between said score lines.

2. A tearing strip can, comprising a body provided with a pair of encircling score lines, and a plurality of tearing strips arranged between said score lines.

3. A tearing strip can, comprising a body 110 provided with a plurality of score lines and

a plurality of tearing strips arranged between said score lines.

4. A tearing strip can, comprising a body provided with a pair of encircling score lines, and a plurality of tearing strip tongues arranged between said score lines, one of said tongues being arranged within the container and the other tongue without it.

10 5. A tearing strip can, comprising a body provided with a pair of encircling score lines, a transverse scoring across the area between said score lines, and tongues permitting independent removal of the strip parts set off by said score lines and on the opposite sides of said transverse scoring.

6. A tearing strip can, comprising a scored body with a tear away area and a plurality of tongues arranged at intermediate points of the length of said area.

7. A tearing strip can, comprising a plurality of successively severable tearing strip parts arranged circumferentially of the can, tearing strip tongues for said parts, and a key adapted to successively engage said tongues.

8. A tearing strip can, comprising a plurality of successively severable tearing strip parts arranged circumferentially of the can,

tearing strip tongues for said parts, and a key adapted to successively engage said tongues and carrying a removed tearing strip part when engaging the second tongue.

9. A blank for a can, comprising a sheet metal member having parallel score lines extending throughout its length, and a transverse score line across the area between said parallel score lines, and a tongue secured to said blank between said parallel score lines and extending across said transverse score lines.

10. A blank for a can, comprising a sheet metal member having parallel score lines extending throughout its length, and a transverse score line across the area between said parallel score lines, a tongue extending out from the area between said parallel score lines at one end and a second tongue secured to the area between said parallel score lines and at said transverse score line and extending in the direction of the first mentioned tongue.

11. A tearing strip can, comprising a scored body adapted to be opened by severance, and a plurality of tearing strip tongues arranged at intermediate points of the strip to be removed.

LEONARD MICHAEL.
